UNITED STATES PATENT OFFICE.

JOHN W. JONES, OF PHILADELPHIA, PENNSYLVANIA.

COMPOUND FOR REMOVING PAINT AND STAINS.

No Drawing. Application filed February 19, 1925. Serial No. 10,883.

This invention is a compound for removing old paint from painted surfaces, and for removing the stains of various kinds from textile fabrics.

For taking stains out of fabrics, the fabric 25 is saturated with the solution described, and allowed to stand or soak for ten minutes; after which the fabric is rinsed out in benzine and dried.

5 The object is to provide a compound for readily and quickly removing old paint from surfaces, and likewise to remove certain stains such as ink stains from garments and the like.

While I have herein described certain 30 fixed proportions for the several ingredients of the solution, it is understood that I may vary the said proportions in any reasonable degree, without departing from the spirit of my invention. However, the proportions 35 as above given are material and substantially fixed, and it is found that better results are obtained from the said proportions than if mixed in other proportions.

10 In carrying out this invention, I provide a solution or liquid compound made up of the following ingredients in substantially equal proportions by bulk or volume measure, and thoroughly mixed together:

I claim:

15 Liquid soap, denatured alcohol of ninety-four per cent proof, chloroform, aqua-ammonia of 38% proof, turpentine, gasoline.

A paint and stain removing solution consisting of equal parts by volume of liquid soap, denatured alcohol, chloroform, aqua ammonia, turpentine, and gasoline.

20 This solution is spread upon the painted surface by means of a brush, and allowed to remain about ten minutes, which results in thoroughly loosening up and dissolving the paint. The loosened paint is then wiped off by means of a cloth saturated with benzine.

In testimony whereof I affix my signature.

JOHN W. JONES.
